UNITED STATES PATENT OFFICE.

VIVIAN JOSEPH GIANELLONI, OF BURTVILLE, LOUISIANA.

CENTRIFUGAL SEPARATOR.

1,166,347.

Specification of Letters Patent. Patented Dec. 28, 1915.

Application filed May 20, 1915. Serial No. 29,369.

To all whom it may concern:

Be it known that I, VIVIAN JOSEPH GIANELLONI, a citizen of the United States, residing at Burtville, in the parish of East 5 Baton Rouge and State of Louisiana, have invented certain new and useful Improvements in Centrifugal Separators; and I do hereby declare the following to be a full, clear, and exact description of the invention, 10 such as will enable others skilled in the art to which it appertains to make and use the same.

My invention relates to improvements in centrifugal separators, especially intended 15 for use in the manufacture of sugar whether from sugar cane or sugar beets, and is more especially intended to provide a centrifugal separator for separating the clear raw juice from the heavier mud and the lighter impurities 20 in a purely mechanical way, in lieu of the mechanical methods now employed.

My invention will be understood by reference to the accompanying drawings, in which the same parts are indicated by the 25 same reference symbols throughout the several views.

Figure 1 shows a sectional elevation of the entire apparatus, parts being shown in central vertical section and parts in elevation; 30 Fig. 2 shows a section along the line 2—2 of Fig. 1, and looking down; Fig. 3 is a modification showing the conical drum mounted in the reversed position from that shown in Fig. 1; and Fig. 4 shows a section along 35 the line 4—4 of Fig. 3, and looking in the direction of the arrows.

Referring first to Figs. 1 and 2, A represents the hollow rotary spindle supporting the separating drum B, which is preferably 40 in the form of a truncated cone having its upper end closed by a diaphragm B', which is provided with a plurality of perforations b, which perforations are arranged in a circle of slightly less diameter than the diaphragm B', as shown most clearly in Fig. 2. The bottom of the drum is closed by a cap C, which is secured to the spindle A in any convenient way, as by the nut D and pin d. The drum B is splined to the spindle A, but 45 is adapted to be raised vertically against the action of the spring Z which tends to draw the drum and cap C together. The rotary drum B is mounted in a suitable casing E which is divided by the annular inclined 50 diaphragm E' into an upper and lower chamber, the lower chamber being adapted

to receive the mud and impure liquor, and the upper chamber being adapted to receive the clarified liquor, which impure and clear liquors are carried off by means of the pipes 60 F and G, respectively. The drum B is provided with a laterally-projecting shelf H, which preferably overhangs the inclined diaphragm E', as shown at H', but this overhanging portion may be omitted if desired. The hollow spindle A is rotated by any suitable means, such as a belt, driven by an electric or hydraulic motor. In the drawings I have shown a pulley A' fast to the spindle A, and driven by a belt, not shown, 70 from any convenient source of power. I is a casting which contains and supports the bearings of the machine. The liquid to be clarified is fed through the pipe K to the interior of the hollow spindle and passes 75 into the drum through the openings L near the bottom of said hollow spindle.

In order to lift the shell of the drum, I provide a collar M attached to the diaphragm B' which is connected by the sleeve 80 N to the double cone piece O, forming one member of a clutch, and the other member of said clutch being in the form of a similar hollow double cone piece P connected by the ears p and pins p' to the links Q, carried 85 by the rods R, which rods pass through the bearing plate S mounted above the supports I, and are attached to the cross head T which is raised and lowered by the eccentric U mounted on the shaft U'. Said eccentric 90 is turned in any convenient way by suitable mechanism, as by the hand wheel U² fast on the shaft U'. It will be seen that when the eccentric is turned to the proper position the shell of the drum B will be lifted 95 clear of the bottom C and any contents in the drum will be thrown outward by centrifugal force, and wedged downward due to the inclined shape of the shell of the drum, supplemented by gravity; while when 100 the eccentric is turned in the reverse position, the cone will be positively held in the closed position.

In the form of device shown in Figs. 3 and 4, the position of the conical drum B is 105 reversed, the closed diaphragm B' being at the bottom and a removable top C' is provided which is lifted in the same way as the shell of the drum already described with reference to Figs. 1 and 2. In this form of 110 device, shown in Figs. 3 and 4, the shell of the drum is fixed to the rotary spindle, while

the top of the drum is removable, and in this case the clear liquid is drawn off through the pipe F' and the mud and impure liquid is drawn off through the pipe G' which is connected to the annular chamber at the base of the inclined partition E'.

5 The casing E, shown in Figs. 1 and 3, may be provided with a suitable cover W, if desired.

10 The operation of the device is as follows:—The liquid, such as raw juice, is fed in through the pipe K, and, entering the hollow spindle A, passes down and out through the opening L into the conical drum, where the mud and heavier solid particles are thrown by centrifugal force outward, occupying a series of concentric cylindrical layers next the conical shell of the drum. This layer of mud begins to 15 settle under the action of centrifugal force at the angle X, see Figs. 1 to 3, and as this layer becomes thicker it extends longitudinally of the conical surface of the drum and inwardly until finally it reaches a position 20 indicated by the dotted line x—x. The clearer liquid is found inside of this layer of mud, while the lighter particle, such as the chips, fiber, or the like, accumulate in a cylindrical layer near the spindle and inside 25 of the clear liquid. This clear liquid escapes through the perforations b—b, and is drawn off to the evaporators, or to any suitable receptacle not shown. As soon as the mud layer passes beyond the line x—x it will 30 begin to muddy the liquid passing through the perforations b, and the evidence of mud in the filtered liquid will automatically advise the attendant that the apparatus needs 35 cleaning.

40 Of course, the machine should ordinarily be cleaned before this. The machine will function a definite length of time, and this time element may serve as a guide as to when to clean. This may be accomplished 45 by cutting off the supply of liquid entering through the pipe K and either lifting the drum B clear of the bottom C, as shown in Fig. 1, or lifting the top C' clear of the drum B, as shown in Fig. 3. The centrifugal force will cause the contents of the 50 drum to be forced outward, carrying away the mud and other impurities past the open mouth of the drum, and these may be carried off through the pipe F of Fig. 1, or G' 55 of Fig. 3, to the filter press or settling tank, or any suitable receptacle not shown.

If it be desired to wash out the apparatus, this may be readily done by supplying water, preferably warm water, through the 60 pipe K and carrying off the water used in washing to the waste. It will be evident that chemicals may also be introduced with the washing water, or with the raw juice, or other liquid to be separated, if desired.

65 By having the drum B in the shape of a

frustum of a cone as shown, the apparatus automatically empties itself, when in motion, of any liquid or semi-liquid matter. Thus it will be seen that a continuous process of a clarification may be carried on indefinitely, with occasional short stops for cleaning out the impurities that accumulate in the inner and outer portions of the mass of liquid that is being rotated with the drum.

70 While the herein described apparatus is especially adapted for the clarification of the raw juice from the sugar cane, or from the diffusion vats in beet sugar factories, it may also be used for clarifying the syrups 75 secured in the subsequent stages of the manufacture of sugar. It may also be used to separate from other liquids than sugar solutions the solid particles or other impurities having different specific gravity 80 from the pure liquor to be clarified.

85 In the manufacture of sugar, it is preferable to use the apparatus rotating about a vertical axis, so that the centrifugal force and gravity will act at right angles to each other on the liquid contents of the drum, thus insuring greater uniformity of action of the apparatus, especially with regard to the concentric cylindrical layers of heavy mud, clear liquid and lighter inner particles.

90 It will be obvious that various modifications might be made in the herein described apparatus and in the construction, combination and arrangement of parts without departing from the spirit of my invention; 100 thus the top W of the outer casing may be omitted in both forms of the structure shown, and the bottom of the outer casing may be open, suitable means being provided to catch mud or liquid, as the case may be, 105 coming from the drum.

I claim:—

1. An apparatus of the character described, comprising a hollow spindle, with means for rotating same, a drum carried by 110 said spindle closed at one end and having a removable head for the other end, one end of said drum being provided with a series of perforations spaced away from the periphery thereof, the said hollow spindle being provided with passages opening into said drum, and means for feeding the liquid to be filtered to said hollow spindle, with means for removing the removable head from said drum, while said drum is being rotated, also 115 for returning the head to the closed position, and also holding the same positively in said closed position while said drum is being rotated, substantially as described.

120 2. An apparatus of the character described, comprising a hollow spindle, with means for rotating same, a drum carried by said spindle closed at one end and having a removable head for the other end, one end of said drum being provided with a series of 125

perforations spaced away from the periphery thereof, the said hollow spindle being provided with passages opening into said drum, means for feeding the liquid to be filtered to said hollow spindle, with means for removing the removable head from said drum, while said drum is being rotated, means for returning the head to the closed position and holding the same positively in said closed position while said drum is being rotated, and a casing surrounding said drum provided with an annular diaphragm, concentric with said drum, and separating said casing into two chambers, substantially as described.

3. An apparatus of the character described, comprising a hollow spindle, with means for rotating same, a drum substantially in the form of a frustum of a cone having an unobstructed inner surface carried by said spindle, said drum having the small end closed and having a removable head for the other end, the small end of said drum being provided with a series of perforations spaced away from the periphery thereof, and the said hollow spindle being provided with passages opening into said drum, and means for feeding the liquid to be filtered to said hollow spindle, substantially as described.

4. An apparatus of the character described, comprising a hollow spindle, with means for rotating same, a drum substantially in the form of a frustum of a cone having an unobstructed inner surface carried by said spindle, said drum having the small end closed and having a removable head for the other end, the small end of said drum being provided with a series of perforations spaced away from the periphery thereof, and the said hollow spindle being provided with passages opening into said drum, and means for feeding the liquid to be filtered to said hollow spindle, with means for removing the larger head of said drum, and means also for returning the same to the closed position when the drum is being rotated, substantially as described.

5. An apparatus of the character described, comprising a hollow spindle, with means for rotating same, a drum substantially in the form of a frustum of a cone having an unobstructed inner surface carried by said spindle, said drum having the small end closed and having a removable

head for the other end, the small end of said drum being provided with a series of perforations spaced away from the periphery thereof, the said hollow spindle being provided with passages opening into said drum, means for feeding the liquid to be filtered to said hollow spindle, and a casing surrounding said drum provided with an annular diaphragm, concentric with said drum, and separating said casing into two chambers, substantially as described.

6. An apparatus of the character described, comprising a hollow spindle, with means for rotating same, a drum substantially in the form of a frustum of a cone having an unobstructed inner surface carried by said spindle, said drum having the small end closed and having a removable head for the other end, the small end of said drum being provided with a series of perforations spaced away from the periphery thereof, the said hollow spindle being provided with passages opening into said drum, means for feeding the liquid to be filtered to said hollow spindle, and a casing surrounding said drum provided with an annular diaphragm, concentric with said drum, and separating said casing into two chambers, with means for removing the larger head of said drum, and means also for returning the same to the closed position when the drum is being rotated, substantially as described.

7. An apparatus of the character described, comprising a hollow spindle, with means for rotating same, a drum carried by said spindle closed at one end and having a removable head for the other end, the closed end of said drum being provided with a series of perforations spaced away from the periphery thereof, the said hollow spindle being provided with passages opening into said drum, and means for feeding the liquid to be filtered to said hollow spindle, with means for removing the removable head from said drum, and means for returning said head to the closed position and holding same there positively, while said drum is being rotated, substantially as described.

In testimony whereof, I affix my signature, in presence of two witnesses.
